UNITED STATES PATENT OFFICE.

JOHN H. COOMBS, OF BOSTON, MASSACHUSETTS.

PISTON WATER-METER.

SPECIFICATION forming part of Letters Patent No. 247,617, dated September 27, 1881.

Application filed April 14, 1881. (Model.)

To all whom it may concern:

Be it known that I, JOHN H. COOMBS, of Boston, in the county of Suffolk and State of Massachusetts, have invented certain new and 5 useful Improvements in Water-Meters, of which the following is a specification.

The objects of my invention are to provide a cheap, simple, durable, and accurate water-meter, which shall register the exact quantity 10 of water passing through the same under any pressure and in any desired size of stream, and which shall operate automatically solely by the pressure of the water upon the piston-heads and the movement of the valves reciprocally 15 therewith; and a further object is to simplify the construction, and thereby reduce the cost, and also reduce the frictional contact-surfaces of the reciprocating piston and valves and the connection and operation of the registering 20 mechanism, whereby durability is insured and accuracy obtained in the measurement of the liquid or operating agent passing or flowing through the same; and it consists in the construction, combination, and arrangement of the 25 main hollow reciprocating valve and the flat sliding auxiliary valve and the communicating passages and their ports with the reciprocating piston and actuating-lever, for imparting the rotative movement to the registering 30 mechanism, as hereinafter more fully described and set forth.

Figure 1 represents a vertical transverse central section of a water-meter embodying my invention. Fig. 2 represents a horizontal longitudinal section of the same. Fig. 3 represents 35 a rear elevation of the main-valve shell or case removed from the piston case or shell. Fig. 4 represents a vertical longitudinal central section of the main valve and its shell or case. Fig. 5 is a plan view of the actuating-lever in 40 position.

A represents the outer shell or cylindric casting, into which is nicely fitted the hollow piston C C', so as to slide back and forth therein 45 and form an air-tight joint with the said shell, the ends of which are suitably closed by the heads A' A'', secured thereto by means of bolts and nuts in the usual manner.

At one side of the shell or case A, and at 50 about mid-length thereof, is provided an inlet, E, having an internal screw-thread, whereby the meter may be connected with a water-pipe,

as heretofore. The shell or case is also provided on its upper portion, and nearly opposite the inlet E, with an opening, D, and internally 55 near each end with passages I I', which lead therefrom toward the center and open outwardly through the same, near the lower portion thereof, into the bottom portion of the main-valve shell P, which is secured to the vertical outer face of the piston-shell A by suitable screw-bolts, so as to form a tight joint. This valve-shell P is provided with a cylindrical bore, into which is fitted the hollow reciprocating valve G, having an opening, F, in its 60 upper side, and two ports or openings, H H', in its bottom, and between these its lower surface or bearing is provided with a transverse passage, which communicates with the outlet S. This valve-shell P is closed at each end by 65 suitable heads, O O', and on its upper surface is provided with a short vertical tube adapted to receive therein the ratchet mechanism connected with the vertical actuating-shaft V, to the lower end of which is connected one end of 70 the horizontal actuating-lever U, the opposite reciprocating end being arranged to contact with the inner heads, B B', of the said hollow piston, and is provided with a broad rounded 75 end, so as to permit the reciprocation of the 80 same with the movement of the piston, as shown in Fig. 5.

The face of the valve-shell P is provided with a flat horizontally-sliding valve, K, having a projecting stem, L, which contacts with the 85 said heads B B' of the piston during a portion of its stroke, as hereinafter described. This flat sliding valve K is held in contact with its seat upon the vertical face of the said valve-shell P by the pressure of the water, and its 90 horizontal movement is guided by a ledge formed on the piston - shell, which forms a groove when the parts are brought together, in which the lower edge of the flat valve K rests and slides when in operation, as follows: The water flows through the inlet E and 95 fills the space between the inner heads, B B', of the reciprocating piston C C', and thence through the opening D of the case or shell A, inclosing the said piston, and through the opening F into the chamber of the main hollow reciprocating valve G, and thence downward 100 through its port H into the passage I, which leads to the space between the outer head, J,

of the piston and the end or head A' of the cylindric shell A, when the pressure of the water therein forces the reciprocating piston C C' nearly to the opposite end or head, A², of the said shell; and just before it reaches the end of its stroke the inner head, B, contacts with the stem L of the sliding flat valve K and moves it sufficiently to open the port N of the passage M, which leads to the space between the end 10 O of the main-valve shell P and the end of the said reciprocating valve G. A small quantity of water entering therein forces the said hollow valve G in the opposite direction to the movement of the piston, and thus opens the 15 outlet-port R to the water contained in the space between the opposite outer head, J', of piston C' and opposite end or head, A², of the said shell A, and in the opposite passage, M', whence it flows from the outlet S. Now, the 20 inlet-water flows into the chamber of the main valve G, as before, and passes downward through its opposite port, H', into the opposite passage, I', leading to the space between the opposite outer head, J', of the piston C' and the end or head A² of the said shell A, so that 25 the pressure of water flowing therein shall cause the said piston C C' to reciprocate, thus operating or reciprocating the said valves G and K, as before described, whereby a constant 30 stream of water is permitted to flow through the meter. The water contained between the end of the main valve G and the end or head O of its shell or case P flows back through its passage and port R, beneath the flat valve K, to the 35 exhaust-port T, and thence through the main outlet S, during the movement or reciprocation of the said valve G.

In order to accurately measure and register the quantity of water thus passing through the

meter, I construct a horizontal lever, U, the free end of which is formed so as to contact loosely between the said inner heads, B B', of the said reciprocating piston C C' in such manner as to impart a corresponding reciprocating movement thereto, its opposite end being 40 connected to the lower end of the vertical shaft V, which may thereby have an intermittent rotative movement imparted to it; and said shaft is provided with a fixed ratchet-wheel containing an odd number or twenty-five teeth, which are acted upon or held by four pawls, some one of which constantly drops within the teeth and contacts therewith, so as to rotate a similar or corresponding loose ratchet-wheel upon said shaft, provided with an odd 45 number or twenty-five teeth, which are acted upon by four pawls holding in the opposite direction, whereby the movement of said lever U communicates a continuous rotary movement to a suitable registering mechanism, as 50 heretofore.

Having thus described my invention, what I claim is—

The combination, with the reciprocating piston having a transverse inlet water-passage 65 between its inner heads, of the flat sliding valve, which contacts with said heads during a portion of said piston's stroke, and the horizontal actuating-arm, arranged as described, and the main hollow reciprocating valve and 70 its shell or case, having the openings, ports, and passages constructed and arranged for operation substantially as shown and described, as and for the purposes set forth.

JOHN H. COOMBS.
